UNITED STATES PATENT OFFICE.

ADOLPH MÜLLER, OF BERLIN, GERMANY.

STORAGE BATTERY.

No. 813,730.

Specification of Letters Patent.

Patented Feb. 27, 1906.

Application filed July 30, 1904. Serial No. 218,816.

To all whom it may concern:

Be it known that I, ADOLPH MÜLLER, a subject of the German Emperor, and a resident of Berlin, Germany, have invented certain 5 new and useful Improvements in Storage Batteries, of which the following is a specification.

Plates which consist of finely-perforated metal sheet or fine metal gauze inclosing 10 blocks of active material all suffer from the disadvantage that, on the one hand, the sheets of gauze are strongly forced apart by the expansion of the active mass, caused by the electrolytic action, thus making the 15 plates thicker, and, on the other hand, the whole grid is very unstable unless a very strong frame is provided, in which case the weight of the grid is disproportionately increased. It has been attempted to overcome 20 this difficulty by pushing stays or strips between the plates after assembling, thus pressing the two perforated covers of each plate together. This not only has the disadvantage of making the construction of 25 the plates more complicated, but also makes it very difficult to change single plates later, since not only has the active material expanded, but by the removing of a single plate all the strips are disarranged, so that it is impossible 30 to insert a new plate in place of the old. The present invention avoids this disadvantage, since the sheets inclosing the active material are so closely bound together at frequent intervals that the strength of the joints 35 is equal to the strength of the sheets.

The invention, stated in general terms, comprises the improvements to be presently described and finally claimed.

The nature, characteristic features, and 40 scope of the invention will be more fully understood from the following description, taken in connection with the accompanying drawings, forming part hereof, and in which—

Figure 1 is a view illustrating a side view 45 of a portion of the plate and indicating that the plate is the same throughout. Fig. 2 is a sectional view drawn to an enlarged scale and taken in a vertical direction through Fig. 1. Fig. 3 is a sectional view of the edge 50 of the plate drawn to a reduced scale and taken in a generally horizontal direction with respect to Fig. 1. Fig. 4 is a similar view taken through another portion of the plate. Figs. 5 and 6 are respectively a plan and a 55 sectional view illustrating a modification of the invention. Fig. 7 is a perspective view

of a blank from which one of the plate-covers is made. Figs. 8 and 9 are sectional views taken at right angles in respect to each other and illustrating means for making the plate, 60 and Figs. 10 and 11 are similar views showing different positions of the means illustrated in Figs. 8 and 9.

The plate or electrode comprises a support or envelop consisting of two perforated covers 1 and 2, within which are contained cakes 3 of active material or material to become active. These covers at their margins are held together by U or similarly shaped reinforcing strips 4, Figs. 3 and 4. At suitable 70 intervals throughout the covers there are loops, through which are inserted pins 5, which may be of material that is not acted upon by the electrolyte. These pins serve not only to firmly bind the two covers together, thus retaining the active material properly, but they also serve to stiffen the plates or impart rigidity to them. The ends of these pins may be inclosed by the strip 4, as shown in Fig. 3. The loops may be variously formed for the reception of the pins. As shown in Fig. 2, the loops 6 and 7 are formed one from each cover-plate and are bent in pairs alternately backward and forward, whereas in Figs. 5 and 6 the loops 8 are 85 bent back from one cover 9 through perforations 10 in the other cover 11. In either event there are formed pockets or corrugations which contain the active material.

For the sake of description an explanation 90 will now be given of one way of making the plate shown in Figs. 1 to 4. The blank shown in Fig. 7 is first made, and two such blanks are placed between the dies 12 and 13. (Shown in Figs. 8 to 11.) These dies are arranged in a suitable press and are provided with movable formers 14 and 15, respectively provided with projections arranged opposite spaces. The dies 12 and 13 and formers 14 and 15 are after the cakes of material 3 have been placed in the pockets or corrugations of the covers pressed together, thus bringing the cover-plates into tight contact with the cakes and also bending back the loops 6 and 7 in the manner described. The formers or plungers 14 and 15 are then withdrawn, as shown in Fig. 11, while the dies 12 and 13 hold the covers firmly to the active material. Thereupon the pins 5 are inserted through the loops. The strips 4 are then applied to the edges of the plate in the manner described. 105 To make the plate shown in Figs. 5 and 6,

the blanks may be provided with perforations in such a way that the perforations in one cover come opposite the projections of the plunger, so that the latter force these projections through them ready for the insertion of the pins.

It will be obvious to those skilled in the art to which the invention relates that modifications may be made in detail without departing from the spirit thereof. Hence the invention is not limited further than the prior state of the art may require; but,

Having thus described the nature and objects of my invention, what I claim as new, and desire to secure by Letters Patent, is—

1. A battery plate-support consisting of perforated covers provided with lateral loops, and having pins inserted through the loops, the relation of the loops being such that the pins lock the covers together, substantially as described.

2. A battery plate-support consisting of perforated covers provided respectively at intervals with loops struck up in the same direction, and having pins inserted through the loops and the intervals between the loops, the relation of the loops and intervals being such that the pins lock the covers together, substantially as described.

3. A battery plate-support consisting of perforated covers provided with lateral loops and having pins inserted through them, and U-shaped strips clamping the edges of the covers and the ends of the pins, the relation of the loops being such that the pins lock the covers together, substantially as described.

4. A battery-plate consisting of cakes of active material, or material adapted to become active, a support or envelop consisting of two perforated covers provided with loops, pins engaging the loops and locking the covers together, and U-shaped marginal strips, substantially as described.

5. A battery-plate consisting of corrugated perforated cover-plates provided with laterally-extending loops, pins engaging the loops and locking the covers together, cakes of active material in the corrugations, and means for clamping the edges of the covers, substantially as described.

Signed at New York city, in the county of New York and State of New York, this 22d day of July, A. D. 1904.

ADOLPH MÜLLER.
